UNITED STATES PATENT OFFICE

162,248

SAFETY SIGHT

Paul H. Sommers, Montgomery, Ala.

Application May 27, 1949, Serial No. 2,917

Term of patent 7 years

(Cl. D14—6)

To all whom it may concern:

Be it known that I, Paul H. Sommers, a citizen of the United States, residing at Montgomery, in the county of Montgomery and State of Alabama, have invented a new, original, and ornamental Design for Safety Sight, of which the following is a specification, reference being had to the accompanying drawing, forming a part thereof.

Figure 1 is a front elevational or plan view of a safety sight embodying my new design.

Figure 2 is a view similar to Figure 1, but showing the safety sight in a reversed or inverted position.

The safety sight comprises, essentially, a thin, flat transparent transfer or sticker for attachment to the windshield of an automotive vehicle. The drawing is lined for color.

I claim:

The ornamental design for a safety sight, substantially as shown and described.

PAUL H. SOMMERS.
